UNITED STATES PATENT OFFICE.

JAMES SPRUCE AND ASA M. COMSTOCK, OF WATERBURY, CONN., ASSIGNEES TO THE SCOVILL MANUFACTURING COMPANY, OF SAME PLACE.

PAIL-EAR.

SPECIFICATION forming part of Letters Patent No. 329,231, dated October 27, 1885.

Application filed June 18, 1884. Serial No. 135,234. (No model.)

To all whom it may concern:

Be it known that we, JAMES SPRUCE and ASA M. COMSTOCK, of Waterbury, in the county of New Haven and State of Connecticut, have invented a new Improvement in Pail-Ears; and we do hereby declare the following, when taken in connection with accompanying drawings and the letters of reference marked thereon, to be a full, clear, and exact description of the same, and which said drawings constitute part of this specification, and represent, in—

Figure 1, an outside view; Fig. 2, an inside view; Fig. 3, a longitudinal central section; Figs. 4 and 5, modifications.

This invention relates to an improvement in the article of manufacture commonly called "pail-ears"—that is to say, the metal socket which is attached to pails, and into which the ends of the bail are introduced as bearings in which the bail will swing.

In the more general construction of this class of ears they are struck from sheet metal, and in outline, as seen in Fig. 1, it being a cup-shaped center, with a flange extending to the right and left, as a means for securing the ear to the pail. In the center of the cup-shaped portion is a hole to receive the end of the bail-wire. The hole in the cup has usually been made by a simple perforation through the bottom of the cup, presenting the edge of the metal to the wire of the bail, and thus giving only the thickness of the metal as a wearing-surface, and unless the metal be very thick and stout the metal surrounding the hole frequently tears out, so as to permit the end of the bail to escape, and as new ears are not generally accessible to those who use the pails, it is practically impossible to properly repair the pail by the application of a new ear.

The object of our invention is to construct the ear so as to present a larger bearing-surface for the bail, as well as greatly strengthen the metal around the bearing; and it consists in the construction of the ear, as hereinafter described, and more particularly recited in the claims.

A represents the cup-shaped center; B, the projections therefrom, by which the ear is secured. The cup-shaped portion is made substantially concavo-convex, as seen in Fig.

3. Instead of cutting away the metal to form the hole, as heretofore practiced, we turn the metal inward, as seen at *a*, Fig. 3, to form an inwardly-projecting tube. Around this tube a wire ring, *b*, is set, and then the metal which has been turned inward is struck down over the ring, and so as to substantially inclose it and firmly attach it to the cup around the hole, and thus form a bearing of considerable thickness, presenting a rounded surface, and strengthened not only by the peculiar shape of the metal turned in, but also by the wire ring introduced.

Instead of introducing a wire ring around the hole, the metal may be rolled upon itself, as seen in Fig. 4, forming a metal bead from the metal itself around the opening, and of substantially the same shape as if a wire were introduced; or, as seen in Fig. 5, instead of turning the metal inward to form the bead around the hole, there may be a flanged tube like an eyelet introduced through the opening, the flange upon the outside, the inner end turned outward and over the wire ring *b*. In any case a smooth rounded surface-bearing is formed, so far strengthening the metal about the hole that the liability to rupture is avoided, and a much lighter metal may be employed than in the usual construction.

We claim—

1. As an article of manufacture, a pail-ear made from sheet metal, consisting of the cup-shaped center *A*, with projections *B* therefrom to secure the ear to the pail, the center pierced to form a bearing for the bail, the bearing re-enforced by the metal turned in from the hole upon the surface of the cup, so as to form a bead around the bearing, substantially as described.

2. A pail-ear made from sheet metal, consisting of the cup-shaped center *A* and projections *B* therefrom, the center pierced to form the bearing, combined with a ring, *b*, around the bearing, the metal being turned over the wire to inclose and secure it in place, substantially as described.

JAMES SPRUCE.
ASA M. COMSTOCK.
